SHUTTLE EYE AND PROCESS OF MAKING THE SAME

Application filed February 15, 1928. Serial No. 254,434.

This invention pertains to loom shuttles and relates more particularly to a shuttle eye and to a process of making the same. In its broader aspects the invention is applicable to shuttle eyes of any usual type but in certain of its more limited aspects is particularly applicable to self-threading shuttle eyes such as are employed in automatic filling replenishing looms.

10 I prefer to make my improved shuttle eye of sheet material and as a first step in the process, I stamp, punch or otherwise prepare a blank of suitable size and configuration, preferably of sheet steel. I then bend 15 this blank at predetermined points, conveniently by the use of dies, thus producing a one-piece eye having substantially all of its essential parts integrally united. Either a right or left-hand eye may be made from 20 the same blank by bending the blank in the appropriate direction. If made of sheet steel, I deem it desirable to case harden the metal, either before or after bending, preferably after bending. In case hardening, 25 I prefer to stop the hardening action before it has extended through the entire thickness of the metal and thus, although the outer surfaces and edges may be glass hard and very resistant to wear by the yarn, the central unhardened layer of metal provides the 30 desired toughness and strength and prevents fracture. Preferably before hardening, the eye or the blank is subjected to a tumbling operation which smooths and slightly rounds 35 the edges and corners, thus dispensing with the usual difficult operation of smoothing and finishing the eye. The sheet metal eye thus formed provides ample space between its side walls for any desired or usual form 40 of tension device and may be furnished with such additional thread-guiding elements, for example, wear-resistant posts, as may be desired. According to one arrangement, a 45 block of metal or the like is disposed between the side walls of the sheet metal eye and this block supports the tension means and holds the side walls in rigidly spaced relation. Preferably the opposite side walls 50 of the eye are of substantially the same height and each wall is provided, preferably

near its rear end, with an inwardly and downwardly directed yarn retainer. These retainers are rigidly spaced apart to permit easy passage of the yarn in threading the shuttle, but are so shaped as substantially to prevent unthreading. These retainers are complementary and adapted respectively to prevent escape of a yarn by ballooning, whether wound either right or left hand on the bobbin. In order certainly to prevent hard or wiry yarn from throwing itself out of the eye under the action of momentum, these retainers have concave surfaces providing forwardly directed horns and I prefer to employ retainers of fish-tail contour similar to the single retainer shown in the application of Daniel O'Hara, Serial No. 243,590, filed December 30, 1927, since retainers of this type operate in either direction of movement of the shuttle.

While the sheet metal construction above described lends itself very conveniently to the production of this type of retainer, it is obvious that similar retainers may be embodied in shuttle eyes of other than sheet metal construction, and I regard such modifications as falling within the scope of my invention. By reason of the novel construction above outlined and hereinafter more fully described, the shuttle eye threads very easily and in accordance with the ideal sequence, that is to say, the thread enters the rear part of the eye before it enters the forward part, and although the thread enters the eye very easily, it is retained therein with certainty under all conditions, even though the thread be hard twisted or of wiry material, for example, rayon. The improved eye is light in weight, easy to apply to the shuttle body, durable, resistant to abrasion by the thread, and at the same time is cheap and easy to construct.

In the accompanying drawings I have shown certain desirable embodiments of my invention by way of example as well as certain steps in the process of making the improved eye, and in the drawings:

Fig. 1 is a fragmentary plan view of one end of a loom shuttle having the improved eye mounted therein;

Fig. 2 is a side elevation, to larger scale, of the improved eye removed from the shuttle;

Fig. 3 is a side elevation from the opposite side of the eye;

Fig. 4 is an end elevation of the eye, looking forwardly from the bobbin cavity;

Fig. 5 is an opposite end elevation;

Fig. 6 is a section, substantially on the line 6-6 of Fig. 1;

Fig. 7 is a plan view of a blank employed in making the eye shown in Fig. 1;

Fig. 8 is a plan view showing a modified construction of shuttle eye;

Fig. 9 is a section to large scale of line 9-9 of Fig. 6; and

Fig. 10 is a section similar to Fig. 9 but showing the result of a later step in the process.

Referring to Fig. 1, the numeral 1 indicates a shuttle body of usual construction having the front end 2; the bobbin cavity 3 adapted to receive the bobbin 4; and the recess 5 for the reception of the shuttle eye. In this instance a left-hand shuttle is illustrated, having its yarn delivery opening at the point 6.

While I contemplate that certain features of my improved shuttle eye may be embodied in eyes formed by casting or similar processes, I have here chosen to illustrate my improved shuttle eye as of sheet metal construction. In accordance with a preferred mode of procedure, I prepare a blank 7, as shown in Fig. 7, from sheet material, for example, sheet steel of suitable gage, such blank being formed by stamping, punching or other suitable process. This blank comprises a portion 8 adapted to form the bottom wall of the shuttle eye, parts 9 and 10 adapted to form the opposite side walls of the shuttle eye, and parts 11, 12 and 13 preferably integral with the wall portion 9. The parts 11 and 12 are adapted to constitute thread-guiding horns in the completed shuttle eye, while the part 13 forms a guide for directing the yarn, during the threading operation, into the eye 14 formed at the forward portion of the wall member 9. The members 9 and 10 are furnished with openings 15 and 16 respectively for the reception of the bolt which secures the eye in the shuttle body.

The lateral edge of the wall portion 10 of the blank is provided, preferably at its rear end, with an integral projection 17, and the wall portion 9 is provided with a similar projection 18. Projections 17 and 18 are preferably furnished with concave forward edges 19 and 20 respectively, whose outer corners form forwardly directed horns, and with concave rear edges 21 and 22 respectively, whose corners form rearwardly directed horns. The outer ends of the projections 17 and 18 are preferably notched, as

shown at 23 and 24 respectively, thus giving the projections 17 and 18 a fish-tail contour. While the notches 23 and 24 are desirable, to facilitate bending of the parts, as herein-after described, they are not necessary and the outer ends of the projections 17 and 18 may, if desired, be substantially straight.

As the next step in the process, after the preparation of the blank, as above described, I prefer to finish the exposed edges of the blank in such a manner as to make them round and smooth, as indicated at 25 (Fig. 9), so that they will not cut or abrade the yarn. While these edges may be rounded and finished in any desired manner (even after substantial completion of the eye), I find that desirable results may be obtained very cheaply, and yet satisfactorily, by tumbling the blanks with a suitable abrasive in a tumbling drum of usual type. While I prefer to tumble the blanks at this stage of the operation, it is possible to perform this step at a later stage. The next step in the process consists in bending the blank so as to bring the wall portions 9 and 10 into substantially parallel relation and perpendicular to the bottom wall 8. The horns 11 and 12 are bent in opposite directions and properly curved to give them the desired configuration as shown, for example, in Figs. 4 and 5. The projections 17 and 18 are also bent to the shape and the relative positions shown in Fig. 4 and when the bending is completed these projections 17 and 18 curve downwardly and inwardly, having concave under surfaces and having their free ends spaced apart to provide a permanently open guide channel 28 leading into the longitudinal yarn passage 29 defined by the walls 9 and 10. The channel 28 is widest at its upper part, gradually narrowing toward the point where it opens into passage 29, the shape of this channel being such that the yarn enters readily into the passage 29 but does not escape easily.

After the blank has been bent, as above described, I next prefer to case harden it so as to provide hard surfaces adapted to endure the abrasive action of the moving yarn without substantial wear. In performing the case hardening operation I prefer to stop it before the hardening action has extended through the entire thickness of the metal, thus leaving a relatively soft and tough core layer providing the desired strength to prevent the shuttle eye from breaking readily when subjected to blows or vibration. This limited hardening action is indicated in Fig. 10 where the central portion 7^a of the metal is relatively soft while the outer skin or layer 7^b may be substantially glass hard. While I prefer to perform this case hardening operation after the blank has been bent, it is possible, by reason of the tough and soft central core to perform the bending 130

operation after the hardening, and I contemplate that this may be a desirable mode of procedure under some circumstances.

After the bending operation I prefer to 5 secure a diagonal yarn guide 30 within the forward portion of the shuttle eye, the ends of this guide being riveted or otherwise attached to the wall member 9 and the bottom member 8 respectively. This guide or post 10 30 may be of any suitable wear-resistant material adapted to guide the yarn on its way to the lateral eye 14. I also prefer to mount a rigid block 31 of wood or metal between the walls 9 and 10 at the rear portion of the 15 shuttle eye, such block having a transverse opening 32 adapted to align with the openings 15 and 16 and to receive the usual bolt 33 by means of which the eye is secured in the shuttle body. This rigid block 31 determines 20 the distance between the walls 9 and 10 when the bolt 33 is tightened and thus determines the minimum width of the channel 28 leading into the thread passage.

The block 31 forms convenient means for 25 supporting a yarn tension device, and I have herein shown this block as having a transverse slot in which a piece of felt 34 or other suitable friction material is mounted. This 30 particular tension device forms no essential part of the present invention and is merely typical of any suitable tension which may be mounted within the open space between the walls 9 and 10.

In Fig. 1, I have chosen to show the bobbin 35 as reverse wound, that is to say, having its yarn so disposed that it unwinds from right to left when looking at the end of the bobbin. During the flight of the shuttle, the unwinding 40 yarn tends to balloon in the direction indicated at Y^1 in Fig. 4, and as indicated in the latter figure the concave retainer member 17 confines the yarn and tends to prevent the latter from escaping upwardly through the channel 28. In the same way, were the yarn 45 wound upon the bobbin with a normal wind, its ballooning action would take place in the direction of the arrow Y^3 in Fig. 4 so that the retainer member 18 would tend to prevent the yarn from passing upwardly 50 through the channel 28.

After the bobbin has been mounted in the shuttle, the first pick of the shuttle to the left, as viewed in Fig. 1, causes the yarn to draw downwardly through the opening 28 55 and thence into the yarn passage 29, the yarn entering the passage 29 at the rear part of the latter before it has had time to pass down around the horn 11 and into the recess 5^a at the forward tip of the shuttle. Upon 60 the beginning of the first pick to the right, the yarn swings laterally from the recess 5^a between the horn 11 and the forward part of the shuttle body, through the passage 35 into the delivery eye 6, the threading operation 65 thus being complete.

When the yarn employed is hard twisted or wiry, it tends to balloon off very freely from the end of the bobbin, and as the shuttle stops at either end of the travel there is a tendency for this loose yarn to 70 loop outwardly, due to its momentum, and thus to escape from the shuttle eye. Thus, for example, as shown in Fig. 1, where the 75 yarn is reverse wound on the bobbin and the bobbin has just completed its pick to the right, the ballooning yarn, which has been more or less in contact with the under surface of the retainer 17, tends to jump forwardly in the form of a loop Y^2 , and upon the next pick to the left this loop might 80 possibly free itself from the shuttle eye were it not for the provision of the concave surface 21 on the rear edge of the retainer 17. This surface with its horn-like extremity engages the yarn loop and prevents it 85 from escaping from the eye. In the same way, at the opposite end of the shuttle path, a loop projecting in the other direction will be caught by the concave front surface 19 of the retainer 17. Likewise, with a normal 90 wind, wherein the ballooning yarn is more or less confined by the retainer 18, the concave surfaces 20 and 22 of the latter prevent escape of a yarn loop formed at the opposite ends respectively of the shuttle path. 95

It is thus evident that my improved 100 shuttle eye provides means for retaining the yarn, whether the bobbin be wound right or left, and whether the yarns loop forwardly or rearwardly. This shuttle eye is 105 very light in weight; it provides adequate space for any desired type of tension device; its surfaces are hard and wear-resistant and yet smooth so that they do not abrade the 110 yarn; it is comparatively cheap to construct; it is rigid and durable; it is of self-threading character and so designed that the yarn first enters its rear end; and it may be made for either a right or left-hand shuttle merely by bending the blank in an appropriate 115 manner.

In Fig. 8 I have shown a slight modification in which the shuttle eye has the parallel side walls 9^a and 10^a, the projecting horn 11^a and the retainer projections 17^a 115 and 18^a. In this instance, the projections 17^a and 18^a are concave only on their forward edges. The device thus provided is adapted to retain a yarn loop Y^4 extending in the direction shown in Fig. 8, but does not provide positive means for retaining a loop 120 thrown in the opposite direction. While in Figs. 1 to 6 I have shown a shuttle eye provided with the lateral horn 12, I may, if desired, omit the horn as illustrated for 125 example in Fig. 8. The type of eye shown in Fig. 8 may be useful under certain conditions, but I prefer to employ that type of eye shown in the other views since the latter provides positive means for retaining the 130

yarn in both directions of movement of the shuttle.

While I have outlined a series of steps constituting one desirable process of making the above shuttle eye, I wish it to be understood that the present invention is not necessarily limited to this precise order of steps, and furthermore I wish it to be understood that the invention is not necessarily confined to a shuttle eye having the specific proportions of parts here shown, or the particular arrangement of the less important parts, or to the materials hereinabove mentioned as desirable for the purpose.

I claim:

1. A shuttle eye having spaced side walls providing a yarn passage between them and a yarn-retaining element projecting inwardly from each wall, each of said elements having forwardly and rearwardly directed horns arranged to prevent the yarn from throwing itself out of said passage by movement in either a rearward or forward direction, respectively.
2. A self-threading shuttle eye comprising spaced side walls providing a yarn-guiding passage between them and a yarn retainer of fish-tail contour projecting inwardly from each wall and extending longitudinally in said yarn-guiding passage, said retainers being adapted respectively to cooperate with yarn from a right or left wound bobbin and to prevent the yarn from throwing itself out of the yarn passage by movement in either a forward or rearward direction.
3. A self-threading shuttle eye comprising a piece of sheet material bent to provide a bottom wall and spaced, substantially vertical side walls defining a yarn passage between them, each side wall having an integral projection extending inwardly from its upper edge, said projections curving downwardly and being oppositely disposed and having their free ends permanently spaced apart thereby providing a downwardly tapering guide channel leading into the yarn passage, the front and rear edges of each of said projections being concavely curved for engagement with the yarn to prevent the latter from throwing itself out of the passage in either a rearward or forward direction.
4. A shuttle eye comprising a piece of sheet material having integral portions constituting a bottom wall and spaced side walls, at least one wall having oppositely directed yarn-guiding horns extending longitudinally relative to said wall, said walls being spaced to provide a yarn passage between them, and rigid means interposed between said walls to keep them in properly spaced relation.
5. A shuttle eye comprising a piece of

sheet material having integral portions constituting a bottom wall and spaced side walls, one wall having portions constituting oppositely directed yarn-guiding horns extending longitudinally relative to said bottom wall, one wall having a lateral guide eye, and a diagonal yarn-guiding post of wear-resistant material uniting the bottom wall and that wall having the lateral guide eye.

6. A blank for use in making shuttle eyes, said blank having portions shaped to form a bottom wall and spaced side walls for the shuttle eye, said blank also having horns, integrally joined to one of the side wall portions, and adapted to extend forwardly and rearwardly respectively in the completed eye.

7. A blank for use in making shuttle eyes, said blank having portions shaped to form a bottom wall and spaced side walls for the shuttle eye, said blank also having a yarn retainer member of fish-tail contour integrally united to each of the side wall portions adjacent to the rear ends of the latter, said yarn retainer member adapted to extend longitudinally in the completed eye.

8. A shuttle self-threading device of sheet metal formed in one piece and provided at its rear end with two forwardly directed non-resilient horn like elements in close proximity directed from opposite sides of the threading slot, each of said elements forming a similarly acting thread trap.

Signed by me at Providence, Rhode Island, this twenty-eighth day of January, 1928.

LUTHER C. BALDWIN.
